UNITED STATES PATENT OFFICE.

ERNST H. BARBER, OF WORCESTER, MASSACHUSETTS.

BATHER'S APPLIANCE.

1,325,607.

Specification of Letters Patent. Patented Dec. 23, 1919.

Application filed March 30, 1918. Serial No. 225,680.

To all whom it may concern:

Be it known that I, ERNST H. BARBER, a subject of the Emperor of Austria, residing at Worcester, in the county of Worcester and Commonwealth of Massachusetts, have invented a new and useful Improvement in Bathers' Appliances, of which the following, taken in connection with the accompanying drawings, is a specification.

10 The present invention relates to a new article of manufacture for the convenience and use of bathers. The invention resides in the provision of a device which enables persons who have on bathing suits, and are 15 without pockets or the like for the carrying of money, to carry money on their person in a safe, convenient and ready manner, and in such a way that it will not interfere with their activity in the water.

20 The invention is described hereinafter in the following specification and illustrated in the accompanying drawings, wherein—

Figure 1 represents the appliance in position on the wrist of a wearer.

25 Fig. 2 is a plan view of the appliance.

Fig. 3 is a side view thereof.

Fig. 4 is a sectional view on the line 4—4, Fig. 2.

Like reference characters refer to like 30 parts in the different figures.

The appliance takes the form of a band of water proof material, adapted to encircle the wrist of the bather, in a manner similar to the strap of a wrist watch. As specifically 35 illustrated herein, the device is shown as a continuous band 1, but it is obvious that the same may, if desired, be divided, and the two meeting ends thereof joined by a buckle or clasp of ordinary construction, not 40 shown.

As a material for the manufacture of this band, I prefer to use rubber, or some other elastic and water-proof material. However, my invention is not limited to the use of 45 such material, since it is obvious that any flexible fabric, leather, or the like, may be employed for the purpose.

At one portion thereof the band 1 has a preferably integral enlargement 2, here 50 shown of circular form. This enlargement 2 is constructed with spaced top and bottom walls 3 and 4, which inclose a flat circular space 5. This space 5 is suitable for the

reception of coins or any other small articles that the wearer may wish to carry with him 55 while attired in his bathing suit, and which articles he would otherwise be unable to carry because of an absence of pockets in said suit. Access to the space 5 is through a slit 6 of suitable length in either the top 60 wall 3 or the bottom wall 4, and preferably the material at the edges of this slit is slightly thicker to increase its firmness and prevent the accidental loss of coins there-through.

If the appliance be made of rubber, or other elastic fabric, which I now deem preferable as a material for the manufacture of the same, the band 1 can be made small enough to be put under slight tension when 70 in place on the wrist of the wearer, it being understood that the elasticity of the material will allow it to be stretched over the hand of the wearer. When thus under tension, the edges of the slit 6 are drawn 75 tightly together, and may even overlap, and thus securely retain the coins in the space 5. When the wearer desires to obtain a coin, he simply stretches back one edge of the slit 6 and extracts the coin, after which 80 the material springs back into place and substantially closes the space 5. For greater safety and protection against the ingress of water to the space 5, the appliance may be reversed on the wrist of the wearer from 85 the position shown in Fig. 1, namely, with the slit 6 facing downward and in contact with the wrist, whereby the continuous unbroken surface of the wall 4 is presented on the outside.

90 I claim,

As a new article of manufacture, a bather's appliance consisting of a band of flexible or elastic material adapted, when encircling the wrist of the wearer, to be 95 distended or stretched, said band having a portion thereof of double thickness to form a pocket, with a slit in one wall of said pocket extending lengthwise of said band, whereby the edges of said slit are drawn 100 together by the tension of said band when in position.

ERNST H. BARBER.
